[57] CLAIM

The ornamental design for a combined portable radio and cassette recorder, as shown and described.

DESCRIPTION

FIG. 1 is a front, top and right side perspective view of a combined portable radio and cassette recorder showing our new design;

FIG. 2 is a rear, bottom and left side perspective view thereof; and

FIG. 3 is a top plan view thereof, with the handle pivoted to horizontal position.

*Fig. 1**Fig. 2**Fig. 3*
